DISHWASHING APPARATUS

Carl W. Funk, Minneapolis, Minn.

Application March 21, 1938, Serial No. 197,131

9 Claims. (Cl. 299—83)

My invention relates to improvements in dishwashing apparatus, an object thereof being to supply a simple, durable and effective apparatus of such nature adapted to be readily applied to the hot and cold water pipes leading to a sink and to provide a spray either of clear water or suds varying in temperature, as may be desired, from that of the water in the cold water pipe to that of the water in the hot water pipe and varying in pressure up to the maximum of that afforded by the water in said pipes.

Another object of the invention is to provide an apparatus of the present nature, including a receptacle having a closed soap chamber adapted to receive clear water and discharge soapy water through a single valve in one position thereof, such valve, in another position, serving to shunt the clear water past said chamber and, in another position, to arrest the flow of water and drain said chamber under atmospheric pressure.

A further feature of the invention resides in providing a receptacle having an upright soap chamber supplied with a water inlet at its bottom and having walls tapered downwardly toward said inlet to subject the contained soap to the water entering the chamber through said inlet.

An additional feature of the invention resides in forming the outlet from the closed soap chamber in such manner that a relatively large quantity of water may be introduced into the chamber through the inlet before the admission of additional water is substantially resisted by the pressure of air trapped in the upper portion of said chamber.

Other objects of the invention reside in the novel combination and arrangement of parts and in the details of construction hereinafter illustrated and/or described.

In the drawings, Fig. 1 is a front elevational view of a dishwashing apparatus embodying my invention, the same being shown as applied to hot and cold water pipes leading through the back board of a sink; Fig. 2 is a side elevational view of the structure shown in Fig. 1; Fig. 3 is a sectional view, in detail, illustrating particularly the soap receptacle of the illustrated apparatus, said view being taken as on the line 3—3 of Fig. 2; Fig. 4 is a detail sectional view taken as on the line 4—4 of Fig. 2, said view showing particularly the valve construction embodied in the soap receptacle; Fig. 5 is a detail view taken as on the line 5—5 of Fig. 4; Fig. 6 is a detail view of said valve construction, said view being similar to the view of said construction shown in Fig. 3,

but with the valve body turned to a different position; Fig. 7 is an elevational view, in detail, of the valve plug illustrated in section in Figs. 3 to 6, incl., and Fig. 8 is a detail sectional view of the spray nozzle illustrated in elevation in Fig. 1 and 5 in perspective in Fig. 2.

Referring to the accompanying drawings in which similar reference characters are employed to designate similar parts throughout the several views, it will be seen that the illustrated embodiment of my invention includes a receptacle 10 mounted upon and connected with branch feed pipes 11, 12, respectively coupled with hot water and cold water feed pipes 13, 14, leading through the back board 15 of a sink and supplying water 15 to a combined hot and cold water faucet 16 having a pivoting spout 17. The branch feed pipe 12 includes a control valve 18 which is screwed into a T-coupling or adapter 19 interposed between the end of the cold water pipe 14 and the faucet 16. Likewise, the branch feed pipe 11 includes a control valve 20 screwed into a T-coupling or adapter similar to the T-coupling 19, such valve being interposed between the end of the hot water pipe 13 and the faucet 16. Each of said valves 18, 20, has a lever 21 for opening and closing the same and for regulating the flow of water therethrough from its respective water pipe.

A coupling 22 connects the branch feed pipes 11, 12, with a valve housing 23 formed integrally 30 with the bottom portion of the receptacle 10. This receptacle is an elongated upright structure substantially eggshaped, the upper portion of said receptacle comprising a closure 24 for an opening 25 at the top of the body proper of said receptacle. 35 A lip 26 about the opening 25 of the receptacle body is encircled by a gasket 27. Trunnions 28 anchored in the body of the receptacle 10 provide bearings for the ends of a pivoting yoke 29 through which is fitted a threaded clamping screw 30 having a finger piece 31. The inner end of this clamping screw 30 is received in a depression 32 formed in the closure 24 axially thereof, said closure being removably clamped against the sealing gasket 27 by means of said clamping screw 30. With the closure 24 removed from the body of the receptacle 10, cakes or slabs of soap may be introduced from the top into the soap chamber 33 within said receptacle, but with said closure 24 clamped in place, the chamber 33 is 45 tightly sealed at the upper portion of the receptacle.

The valve casing 23 is formed with a horizontally disposed tapered bore 34 and fitting this bore is a correspondingly tapered valve plug 35, 55

the large end of which is formed with a recess 36 therein. A thrust plug 37 axially aligned with the valve plug 35 is threaded into the valve casing 23 and formed with a recess 38 opposing the recess 36 in said valve plug. Contained within said recesses and backed at its outer end against the thrust plug 37 is a compression spring 39 into the inner end of which is fitted a thrust head 40. This thrust head 40 and said valve plug 35 are formed with opposed depressions 41, 42, which receive opposite portions of a thrust ball 43, the action of said compression spring 39, thrust head 40 and thrust ball 43 being to maintain a tight fit between the valve plug 35 and the tapered bore 34 of the valve casing 23, yet permit the tuning of said valve plug. Secured to the small end of the tapered valve plug 35 is a handle 44 for turning said plug. This handle 44 is secured to the plug 35 by means of a fastening screw 45 passing through said handle and threaded into said plug, relative rotation between handle and plug being precluded by means of a key-pin 46 accommodated at its inner end in a bore 47 in said plug 35 and at its outer end in a bore 48 in said handle. The valve plug 35 has a diametrical bore 49 therein and at one side thereof a circumferentially extending channel 50. At the other side of said diametrical bore 49, said valve plug 35 is formed with a longitudinally extending channel 51.

The valve casing 23 is formed with a feed port 52 into which the coupling 22 is threaded. In line with said feed port and formed in the bottom of the receptacle 10 is an inlet port 53. Said feed port 52 and said inlet port 53 are brought into communication for conducting water from the branch feed pipes 11, 12, into the soap chamber 33 within the receptacle 10. To thus bring said feed port 52 and inlet port 53 into communication, the valve plug 35 is turned into a "suds" position, wherein the diametrical bore 49 in said plug registers with said feed port 52 and inlet port 53 (Fig. 3). The said casing 23 is additionally formed with a delivery port 54 into which the coupling member 55 of a spray tube 56 is threaded and said casing is further formed with an outlet port 57 in the bottom of the receptacle 10, said outlet port 57 and said delivery port 54 being brought into communication in the "suds" position of the valve plug 35 through the circumferentially extending channel 50 in said valve plug 35. Issuing upwardly into the receptacle 10 from the outlet port 57 is a tubular extension 58, which is closed at the top thereof, but formed at its upper portion with a plurality of perforations 59 bringing the chamber 33 within the receptacle 10 into communication with the bore of said tubular extension 58. The inlet port 53 is disposed co-axially of the soap receptacle 10 and the inner wall surfaces of said receptacle, at the lower portion thereof, slope inwardly toward said inlet port 53 in order that the cakes or slabs of soap contained within the receptacle chamber 33 will be directed, in gravitation, to the bottom of said chamber into position immediately above or near said inlet port 53. The tubular outlet extension 58 issues from the outlet port 57 at an angle to the axis of the soap receptacle 10 and occupies a position closely adjacent to the sloping wall surface of said receptacle chamber, whereby the pieces of soap within the receptacle are not interfered with by said extension 58 in their descent in the receptacle chamber to position above the inlet port 53. With the valve plug 35 in the "suds" position, as shown

in Fig. 3, the water from one or both of the branch feed pipes 11, 12, under desired regulation, enters the soap chamber 33 where it is saponified and thence directed into the spray tube 56.

The circumferential channel 50 in the valve plug 35 brings the feed port 52 into direct communication with the delivery port 54 in a "clear" position of the valve plug 35, as best shown in Fig. 6. Functioning to thus bring said feed and delivery ports 52, 54, into communication, the channel 50 in the valve plug 35 shunts the water fed from the branch feed pipes 11, 12, into the spray tube 56 in order that such water will not be subjected to the soap within the receptacle 10.

In addition to the "suds" and "clear" positions of the valve plug 35 previously noted, said plug may be turned into a third or "drain" position, best shown in Fig. 4. In said "drain" position of the valve plug 35, the diametrical bore 49 therein registers with the delivery port 54 and also with a drain port 60 formed in the bottom of the soap receptacle 10. Any water contained in said receptacle drains therefrom through said drain port 60, diametrical bore 49 in valve plug 35, and delivery port 54 into the spray tube 56. This drainage of the water from the soap receptacle 10 is initially enhanced by such air as may be trapped under pressure in the upper portion of the soap chamber 33 in receptacle 10. Subsequently, and when this air becomes of the same pressure as that of the atmosphere, air from the outside is admitted into the receptacle chamber 33 through the outlet extension 58 so that the drainage from the receptacle may continue unimpeded. To provide for the admission of air into the interior of the receptacle chamber 33, an air ingress port 61 is formed in the valve casing 23. This port 61 communicates with the outlet port 57 through the longitudinally extending channel 51 in the valve plug 35, said air port 61 being supplied with a valve cage 62 in which a ball check 63 is contained, said ball check operating to prevent the escape of air and/or water through said air port 61, but permitting the ingress of air therethrough.

Fixed to the front of valve housing 23 is a plate 64 bearing the designations "suds," "clear" and "drain" with reference to which the handle 44 of the valve plug 35 is turned to supply soapy water or clear water through the spray tube 56, or to drain the soap receptacle through said tube.

Any suitable nozzle may be provided at the end of the spray tube, such as that shown in detail in Fig. 8 and designated by the numeral 65. This nozzle includes a tubular handle 66, in which the terminal portion of the spray tube 56 is contained, said tube being connected with a nipple 67 issuing from a body 68 threaded within said handle 66. A head 69 formed with fine spray forming perforations 70 and threaded on the body 68 clamps a cup-shaped scraper member 71 between it and the end of said handle 66.

When the valve plug 35 is turned into its "suds" position, after the receptacle has been drained, water from one or the other or both of the branch feed pipes 11, 12, according to the adjustment of the valves 21 in said pipes, enters the receptacle 10 through the feed and inlet ports 52, 53, and the diametrical bore 49 in said plug, the air within said receptacle chamber 33 being driven out of the same through the spray tube 56 until the level of the water in said receptacle seals the perforations 59 in the tubular outlet extension 58. The

further supply of water, subsequently accumulating in the receptacle chamber 33, being added under the pressure of the air trapped in the upper portion of said chamber. Thus, it will be seen 5 that by locating the perforations 59 in the tubular outlet extension 58 at an elevation substantially above the bottom of the receptacle chamber 33, a substantially greater amount of water is provided within the receptacle for contact with the soap therein than would be provided were the outlet from the receptacle chamber to be sealed immediately upon the initial influx of water into said chamber. This provision, 10 wherein a substantial quantity of water is at all times subjected to the soap contained in the container, promotes the active and thorough saponification of the water passing through said receptacle.

Changes in the specific form of my invention, 20 as herein disclosed, may be made within the scope of what is claimed without departing from the spirit of my invention.

Having described my invention, what I claim as new and desire to protect by Letters Patent is:

1. Apparatus of the character described comprising a receptacle forming a mixing chamber and having an opening therein for the introduction of soap into said chamber, a closure for said opening, said receptacle having a valve casing 25 at the base thereof, a valve plug fitted in said casing and adapted to be turned, selectively, into any one of three positions, one a "suds" position, another a "clear" position, and a third a "drain" position, said valve plug being formed with a 30 diametrical bore therein, a circumferentially extending channel and a longitudinally extending channel, said casing having a feed port, an inlet port leading to said chamber, an outlet port leading from said chamber, and a delivery port, said feed port communicating with said inlet port through the bore in said plug and said outlet port communicating with said delivery port through said circumferential channel in the "suds" position of said plug, said casing having 35 a drain port leading from said chamber and communicating with said delivery port through said bore in said plug and having an air inlet port bringing the chamber into communication with the outer atmosphere through said outlet port and said longitudinal channel in said "drain" position of the plug, a check valve in said air inlet port, said feed port communicating with said delivery port through said circumferential channel in said "clear" position of said plug.

2. Apparatus of the character described comprising a receptacle forming a mixing chamber and having an opening therein for the introduction of soap into said chamber, a closure for said opening, said receptacle having a valve casing 45 at the base thereof, a valve plug fitted in said casing and adapted to be turned into a "suds" position and into a "drain" position, said valve plug being formed with a diametrical bore therein, a circumferentially extending channel and a longitudinally extending channel, said casing having a feed port, an inlet port leading to said chamber, an outlet port leading from said chamber, and a delivery port, said feed port communicating with said inlet port through the bore in 50 said plug and said outlet port communicating with said delivery port through said circumferential channel in the "suds" position of said plug, said casing having a drain port leading from said chamber and communicating with said delivery port through said bore in said plug and

having an air inlet port bringing the chamber into communication with the outer atmosphere through said outlet port and said longitudinal channel in said "drain" position of the plug, and a check valve in said air inlet port. 5

3. Apparatus of the character described comprising a receptacle providing a closed soap chamber therein, said receptacle having a valve casing incorporated in the base thereof, a rotatable valve plug in said casing, said casing and plug providing a feed passageway for conducting water into said chamber and a delivery passageway for conducting soapy water therefrom in one position of said plug in said casing, and providing a passageway for water by-passing said soap chamber in another position of said plug in said casing, and providing a drain passageway leading from the soap chamber and an air admission passageway leading into said chamber from the outside in a third position of said plug in said casing. 10 15

4. Apparatus of the character described comprising a receptacle providing a closed soap chamber therein, said receptacle having a valve casing incorporated in the base thereof, a rotatable valve plug in said casing, said casing and plug providing a feed passageway for conducting water into said chamber at the bottom thereof and a delivery passageway for conducting soapy water therefrom in one position of said plug in said casing, said delivery passageway including a conduit opening into the interior of said chamber above the point of ingress of water thereto, whereby a substantial quantity of air 20 may be displaced from the chamber by a similar quantity of water accumulating therein before said delivery passageway is sealed against the further displacement of such air by additional water accumulating in said chamber, said casing and plug providing a drain passageway leading from the soap chamber and an air admission passageway leading into said chamber from the outside in another position of said plug in said casing. 25 30 35

5. Apparatus of the character described comprising a receptacle providing a closed soap chamber therein, said receptacle having a valve casing incorporated in the base thereof, a rotatable valve plug in said casing, said casing and plug providing a feed passageway for conducting water into said chamber at the bottom thereof and a delivery passageway for conducting soapy water therefrom in one position of said plug in said casing, said delivery passageway including a conduit formed with perforations therein opening into the interior of said chamber at different levels, the lowermost level being above the point of ingress of water into said chamber, whereby a substantial quantity of air may be displaced from the chamber by a 40 similar quantity of water accumulating therein before said delivery passageway is sealed against the further displacement of such air by additional water accumulating in said chamber, said casing and plug providing a connection between 45 said feed and delivery passageways by-passing said soap chamber in another position of said plug in said casing, and providing a drain passageway leading from the soap chamber and an air admission passageway leading into said chamber from the outside in a third position of said plug in said casing. 50 55 60

6. Apparatus of the character described comprising a receptacle forming a mixing chamber and having an opening therein for the introduc- 65 70 75

tion of soap into said chamber, a closure for said opening, said receptacle having a valve casing at the base thereof, a valve plug fitted in said casing and adapted to be turned, selectively, into any one of three positions, one a "suds" position, another a "clear" position, and a third a "drain" position, said valve plug being formed with a diametrical bore therein, a circumferentially extending channel and a longitudinally extending channel, said casing having a feed port, an inlet port leading into said chamber at the bottom thereof, an outlet port leading from said chamber and open to the interior thereof at an elevation above said inlet port, and a delivery port, said feed port communicating with said inlet port through the bore in said plug and said outlet port communicating with said delivery port through said circumferential channel in the "suds" position of said plug, said feed port communicating with said delivery port through said circumferential channel in the "clear" position of said plug, said casing having a drain port leading from said chamber at the bottom thereof and communicating with said delivery port through said bore in said plug and having an air inlet port bringing the chamber into communication with the outer atmosphere through said outlet port and said longitudinal channel in said "drain" position of the plug, said plug in said "drain" position serving to obstruct said feed port.

7. Apparatus of the character described comprising a receptacle forming a mixing chamber and having an opening therein for the introduction of soap into said chamber, a closure for said opening, said receptacle having a valve casing at the base thereof, a valve plug fitted in said casing and adapted to be turned, selectively, into a "suds" position and a "drain" position, said valve plug being formed with a diametrical bore therein, a circumferentially extending channel and a longitudinally extending channel, said casing having a feed port, an inlet port leading into said chamber at the bottom thereof, an outlet port leading from said chamber, and a delivery port, said feed port communicating with said inlet port through the bore in said plug and said outlet port communicating with said delivery port through said circumferential channel in the "suds" position of said plug, said casing having

a drain port leading from said chamber and communicating with said delivery port through said bore in said plug and having an air inlet port bringing the chamber into communication with the outer atmosphere through said outlet port and said longitudinal channel in said "drain" position of the plug, said plug in said "drain" position serving to close said feed port.

8. In apparatus of the character described, a closed receptacle providing a mixing chamber, a ported valve casing communicating with said chamber through ports including a liquid inlet, an air inlet, and a liquid outlet, and a ported rotatable valve plug in the valve casing, said casing and plug, in one position of the latter within the former, providing a passageway opening said liquid inlet for the feeding of liquid to said receptacle and opening the outlet for the delivery of the liquid from said receptacle, said casing and plug, in a second position of the latter within the former, providing a passageway establishing direct communication between the liquid inlet and outlet by-passing said mixing chamber, said casing and plug, in a third position of the latter within the former, closing said liquid inlet and providing two passageways, one thereof opening said outlet for draining liquid from said receptacle, and the other thereof opening said air inlet for the admission of air into said receptacle to facilitate drainage thereof.

9. In apparatus of the character described, a closed mixing receptacle, a ported valve casing communicating with said receptacle through ports including a liquid inlet, an air inlet and a liquid outlet, a ported rotatable valve plug in the valve casing, said casing and plug, in one position of the latter within the former, providing a passageway opening said liquid inlet for the feeding of liquid to said receptacle and opening the outlet for the delivery of liquid from said receptacle, said casing and plug, in another position of the latter within the former, closing said liquid inlet and providing two passageways, one thereof opening said outlet for draining liquid from said receptacle, and the other thereof opening said air inlet for the admission of air into said receptacle to facilitate drainage thereof.

CARL W. FUNK.
